Atty's.

UNITED STATES PATENT OFFICE

LAURA FLENTYE, OF WILMETTE, ILLINOIS

HANDKERCHIEF-DRYING FRAME

Application filed April 14, 1927. Serial No. 183,814.

This invention relates to handkerchief drying frames and the like.

An object of the invention is to provide a suitable drying frame for handkerchiefs and like articles, which can be clasped or folded into a small space so that it can be readily stored away in a trunk or suit case.

This and other objects as will hereinafter appear, are accomplished by this invention which is fully described in the following specification and shown in the accompanying drawings, in which:

Figure 1 is a front elevation of the drying frame in use with a handkerchief stretched thereon;

Fig. 2 is an enlarged perspective of the frame folded; and

Fig. 3 is an enlarged section on the line 3 of Fig. 1.

The embodiment illustrated comprises a frame made up of four similar arms 10 of wood or the like, secured together at one end by means of a bolt 11, and wing nut 12.

The outer ends of the arms 10 are covered with a suitable fabric 13 which is drawn tightly thereon so as to be retained thereon. It will be observed that the fabric covers 13 are slidably secured to the outer ends of the arms 10 and are removable therefrom.

In use, the arms are set at right angles to each other as shown in Fig. 1, after which the wing nut 12 is tightened on the bolt 11 so as to retain them in this position. A handkerchief A is then spread over the frame and secured at its four corners to the fabric 13 as by means of pins 14.

A number of handkerchiefs may thus be dried at one time by being superimposed one upon the other, the smaller handkerchiefs being placed on the frame first and the larger size later so as to prevent as far as possible the necessity for pinning through handkerchiefs already on the frame in order to secure another on top of them.

It will be understood, of course, that the

handkerchiefs may be applied to this frame in various ways. After so securing them, the frame is stood up on a dresser or in front of a window so as to insure the complete drying of the handkerchiefs.

When so dried, the handkerchiefs will be found to be very flat and smooth so that it is not necessary to iron them.

The frame may be folded as shown in Fig. 2 when not in use so that it may be placed in a suit case or trunk and occupies very little space.

This device is particularly useful to one who is traveling as it is often quite difficult to get laundry work done at convenient times.

While I have shown and described but a single embodiment of this invention, it is to be understood that it is capable of many modifications. Changes therefore in the construction and arrangement may be made which do not depart from the spirit and scope of the invention as disclosed in the appended claims.

I claim:

1. A collapsible drying frame comprising more than two members hingedly secured together at one end, means for fastening them in the open and closed positions, and a removable cloth cover secured to said frame for securing an article to be dried.

2. A collapsible drying frame for handkerchiefs comprising four substantially straight flat members hingedly secured together at one end so as to permit folding, means for securing said members in the open and folded positions, and a removable cloth cover secured to the outer end of each member to enable a handkerchief to be pinned thereon when said members are in open position.

3. A collapsible drying frame for handkerchiefs and the like, comprising four members secured together at their inner portions, each adapted to stand substantially at right angles to the adjacent members to form a cross, and

a removable cloth cover enveloping the end of each member.

4. A collapsible drying frame comprising more than two members hingedly secured together at one end, means for fastening them in the open and closed positions, and a cloth cover slidably secured on the end of each of said members for securing an article to be dried.

10 In testimony whereof I have hereunto set my hand, this 11th day of April, 1927.

LAURA FLENTYE.
